Primary Examiner — Catherine A Tuttle*(74) Attorney, Agent, or Firm* — Melissa G. Krasovec(57) CLAIM

The ornamental design for a bottle with spray head, as shown and described.

DESCRIPTION

FIG. 1 is a perspective view showing our new design for a bottle with spray head;

FIG. 2 is a front view thereof;

FIG. 3 is a back view thereof;

FIG. 4 is a right side view thereof;

FIG. 5 is a left side view thereof; and,

FIG. 6 is a top view thereof.

The broken lines are included for the purpose of illustrating a portion of the bottle with spray head that forms no part of the claimed design.
